KNIFE

Edward K. Madan, Maplewood, N. J.

Application August 1, 1941, Serial No. 404,991

5 Claims. (Cl. 30—165)

This invention relates to knives, and more particularly to household knives for use in cutting cheese, pie, cake, fruit and other things having a tendency to cling to the knife, making cutting difficult as well as spoiling the appearance of the material cut.

An object of the present invention is to provide a knife having a series of alternate indentations and raised portions on the side or sides of the knife blade, with the adjacent indentations and raised portions merging, by gradual inclined slopes, one into the other, to form vacuum breaking surfaces and prevent material being cut from clinging to the blade, while the sloping conjunction between the indentations and raised portions provides a smooth, uninterrupted surface for the side of the knife blade which eliminates crevices in which material can collect and permits the knife to be easily and quickly cleaned, as by wiping it with a damp cloth in lengthwise strokes or motions. The raised portions decrease in width and thickness from inwardly of the back of the knife blade toward the cutting edge and gradually merge into the blade proper substantially in points a short distance inwardly of the cutting edge.

Another object of the present invention is to provide a knife which is made of molded material, preferably a plastic, so that the entire knife, including the handle, may be made in a single piece and with one molding operation, thereby providing a practical and inexpensive knife.

With these and other objects in view, as may appear from the accompanying specification, the invention consists of various features of construction and combination of parts, which will be first described in connection with the accompanying drawings, showing knives of the preferred form embodying the invention, and the features forming the invention will be specifically pointed out in the claims.

In the drawings:

Figure 1 is a side elevation of a knife constructed in accordance with the present invention and designed particularly for use in cutting cheese or like material.

Figure 2 is a cross-sectional view on the line 2—2 of Figure 1.

Figure 3 is a cross-section through the knife on the line 3—3 of Figure 1.

Figure 4 is a cross-section through the knife on the line 4—4 of Figure 1.

Figure 5 is a cross-section through the knife on the line 5—5 of Figure 1.

Figure 6 is a fragmentary longitudinal section on the line 6—6 of Figure 1.

Figure 7 is a side elevation of a modified form of the knife designed for general utility and particularly for use in cutting fruit.

Figure 8 is a cross-section through the knife on the line 8—8 of Figure 7.

Figure 9 is a cross-section on the line 9—9 of Figure 7.

10. Figure 10 is a plan view of a further modified form of the knife showing a knife particularly adapted for use in cutting pie, cake or the like.

Figure 11 is a cross-section on the line 11—11 of Figure 10.

15. Figure 12 is a cross-section on the line 12—12 of Figure 10.

Referring more particularly to the drawings, the improved knife shown in all of the forms of the drawings is made of a moldable material, such as plastic, glass, or the like, and preferably of plastic, because of its non-breakable qualities and its adaptability to molding.

The form of knife shown in Figures 1 to 6 inclusive is particularly adapted for use in cutting cheese or the like, and it includes a blade 10, which is formed integrally with the handle 11, the entire knife being molded in a single operation and all in one piece. The handle 11 is off-set laterally from the blade 10 so as to facilitate firm gripping and cutting action of the knife. The knife handle 11 has a down-turned nib 12 at the outer end thereof, extending downwardly, the inner edge of which is curved, as shown at 13, to fit the little finger of the user, while the joining portion 14, between the handle 11 and blade 10, at the top or back edge of the blade, is inclined and substantially flat on top. The handle 11 is of such length that it will approximately fit the hand of the user, with the four fingers gripped beneath the lower edge of the handle and the thumb resting upon the inclined joining portion 14, thereby permitting a firm, positive grip on the knife during cutting operations.

45. The blade 10 of the knife has alternately arranged indentations 15 and raised portions 16 extending along its length and upon both sides of the blade, as shown in Figures 2 to 6 inclusive. The general outline of the alternate indentations and raised portions along the length of the blade is sinuous, and the indentations 15 merge into or join the adjacent raised portions 16 by gradual inclined slopes, indicated at 17. They also merge into the blade 10 a short distance inwardly of the back edge of the blade,

through the medium of the gradually inclined slopes 17, said slopes being continuous about the inner edge portions of the indentations of the blade. The raised portions 16 gradually decrease in width and in thickness from their innermost portions a short distance inwardly of the back of the knife blade toward the cutting edge and gradually merge into the blade proper substantially at points a short distance inwardly from the cutting edge. By means of this construction, all abrupt surfaces on the sides of the knife blade are eliminated, and the various surfaces gradually merge, one into the other, so that there will be no crevices or corners in which material may collect. It also provides a knife blade which may be easily cleaned, in the same manner as a perfectly smooth, flat blade, i. e. by longitudinal wiping movement with a cloth, and at the same time the alternate indentations and raised portions will prevent cheese or other similar material being cut from adhering to the blade of the knife while such material is being cut, or afterward.

While the form of knife shown in Figures 1 to 6 inclusive of the drawings is particularly adaptable for cutting cheese or the like, owing to the relative construction of the handle and blade which permits firm gripping of the knife and a rocking, cutting action, the knife shown in Figures 7 to 9 inclusive of the drawings may also be used for the same purpose, though it is more of a general utility knife for use about the kitchen, being adapted particularly for use in cutting fruits and various other articles. Since these knives are made of plastic, they are particularly adaptable for use in cutting various types of fruits, owing to the fact that the knife is not acted upon by the acid of the fruit and will not cause a darkening or staining of the cut surfaces of the fruit. In this modified form of the invention, shown in Figures 7 to 9 inclusive, the handle 20 and the blade 21 are formed in substantially longitudinal alignment, and at their junction the edges of the knife are provided with indentations 22 and 23, in which the thumb and forefinger of the user fit, when using the knife, thus providing for a firm, comfortable grip on the knife. The blade 21, like the blade 10, is provided with alternate indentations 24 and raised portions 25, which extend along the sides or side faces of the blade, and are joined one to the other by sloping, joining surfaces 26, corresponding to the surfaces 17, so that while the sides of the knife blade are provided with vacuum-breaking, non-sticking surfaces, nevertheless the knife may be quickly and easily washed and cleaned. The construction of the alternate indentations 24 and raised portions 25 is the same as the construction of the alternate indentations 15 and raised portions 16. The 60 knife blade 21 is shown as having a saw-tooth cutting edge 27, while the blade 10 is shown as having a smooth cutting edge, but it is to be understood that the cutting edges of either of these blades may be saw-toothed or smooth, as desired, without departing from the spirit of the present invention.

Figures 10 to 12 illustrate a further modified form of the invention. This knife is particularly adaptable for use in cutting cake, pie, pastries, and the like, and the blade 30 of this knife is formed in the shape of a spatula—that is, it is broad and flat, with the handle 31 projecting longitudinally from the center of the broad, blunt end of the blade. The blade 30 has two

cutting edges 32 and 33 along its opposite edges, which merge at the tip of the blade, as shown at 34. One of these edges may be saw-toothed or serrated, as shown at 35, while the other may be smooth. One side of the blade 30 is flat, as shown at 36, while the other side is provided with a row of alternate indentations 37 and raised portions 38 for each of the cutting edges, with the broad or wide portions of the indentations 37 facing the knife edge, and the points of the raised portions facing the knife edge. That is, the blade 30 is provided with two rows of alternate indentations and raised portions, on one side thereof, each row being provided for conjunction with one of the cutting edges. These alternate indentations and raised portions 37 and 38 are joined together and merge into each other and into the knife blade proper by the gradual slopes 39, so that the side of the blade 30 provided with these alternate indentations and raised portions will, like the blades 10 and 21, provide a non-sticking surface without any crevices, corners or abrupt joints in which material may collect, and will permit the blade to be quickly, easily and conveniently cleaned.

The blade 30, being flat to a substantial degree, will permit the knife to be used as a lifter for lifting the pieces of pie, cake or the like after cutting.

It will be understood that the invention is not to be limited to the specific construction or arrangement of parts shown, but that they may be widely modified within the invention defined by the claims.

35 What is claimed is:

1. As a new article of manufacture, a knife including a blade having a series of alternate indentations and raised portions extending along the side face of the blade with the adjacent indentations and raised portions merging by gradual inclined slopes to provide a non-sticking knife blade free from abrupt surfaces and crevices, said raised portions gradually decreasing in thickness and width from their back portions towards the cutting edge of the knife blade, said indentations terminating short of the back edge of said blade and merging into the blade by gradual inclined slope at their back portions.

2. As a new article of manufacture, a knife including a blade having a series of alternate indentations and raised portions extending along the side face of the blade with the adjacent indentations, and raised portions merging by gradual inclined slopes to provide a non-sticking knife blade free from abrupt surfaces and crevices, said raised portions gradually decreasing in thickness and width from their back portions towards the cutting edge of the knife blade and terminating substantially in points flush with the face of the blade adjacent to the cutting edge.

3. As a new article of manufacture, a knife molded in one piece of plastic material and including a blade having a series of indentations and raised portions extending along the side face of the blade with the adjacent indentations and raised portions merging laterally by gradual inclined slopes to provide a non-sticking knife blade without abrupt surfaces and crevices, said raised portions gradually decreasing in thickness and width from their back portions toward the cutting edge of the blade and terminating approximately flush with the surface of the blade adjacent to the cutting edge.

4. As a new article of manufacture, a knife

having a blade in the form of a spatula, and having cutting edges on both edges of the blade, said blade provided with a series of alternate indentations and raised portions on one side face of the blade and extending along each portion of the blade adjacent to its two cutting edges, the adjacent indentations and raised portions merging into each other and into the blade face by gradual inclined slopes to provide a non-sticking knife blade without abrupt surfaces or crevices, the side face of said blade opposite to the one provided with said alternate indentations and raised portions being flat and smooth.

5. In a new article of manufacture, a knife including a blade having a series of alternate indentations and raised portions extending along the side face of the blade, said raised portions gradually decreasing in thickness and width from their back portions toward the cutting edge of the blade and terminating substantially in points flush with the face of the blade adjacent to the cutting edge.

EDWARD K. MADAN.
